US00D798888S

(12) **United States Design Patent** (10) Patent No.: **US D798,888 S**
(45) Date of Patent: ** Oct. 3, 2017

(54) **TOUCHSCREEN DEVICE WITH
GRAPHICAL USER INTERFACE**

(71) Applicant: **CANONICAL LIMITED**, Douglas (IM)

(72) Inventors: **Mark Shuttleworth**, Douglas (IM); **Ivo Weevers**, Douglas (IM); **Mika Meskanen**, Douglas (IM); **Oren Horev**, Douglas (IM); **Calum Pringle**, Douglas (IM); **John Lea**, Douglas (IM); **Otto Greenslade**, Douglas (IM); **Marcus Haslam**, Douglas (IM); **Ivanka Majic**, Douglas (IM); **Xi Zhu**, Douglas (IM)

(73) Assignee: **Canonical Limited**, London (GB)

(**) Term: **14 Years**

(21) Appl. No.: **29/477,484**

(22) Filed: **Dec. 23, 2013**

(51) LOC (10) Cl. **14-04**

(52) U.S. Cl.

USPC **D14/486**

(58) **Field of Classification Search**

(57) **CLAIM**

The ornamental design for a touchscreen device with graphical user interface, substantially as shown and described.

DESCRIPTION

The FIGURE is a front view of a touchscreen device with graphical user interface showing our new design; The outermost broken line illustrates the touchscreen device. The innermost broken lines illustrate a Display Screen. None of the broken lines form part of the claimed design.

1 Claim, 1 Drawing Sheet
